(No Model.)

J. E. EMERSON & T. MIDGLEY.
WIRE MAT.

No. 462,941.

Patented Nov. 10, 1891.

UNITED STATES PATENT OFFICE.

JAMES E. EMERSON AND THOMAS MIDGLEY, OF BEAVER FALLS, PENNSYLVANIA.

WIRE MAT.

SPECIFICATION forming part of Letters Patent No. 462,941, dated November 10, 1891.

Application filed August 22, 1891. Serial No. 403,379. (No model.)

To all whom it may concern:

Be it known that we, JAMES E. EMERSON and THOMAS MIDGLEY, citizens of the United States, residing at Beaver Falls, in the county 5 of Beaver and State of Pennsylvania, have invented certain new and useful Improvements in Wire Mats; and we do hereby declare the following to be a full, clear, and exact description of the invention, such as will enable others skilled in the art to which it appertains to make and use the same.

Our invention relates to wire mats, and has for its object certain improvements in construction, which will hereinafter appear.

15 In the accompanying drawings, which form part of this specification, we have illustrated the best form in which we have contemplated embodying our invention, and the invention will be fully disclosed in the following specification and claims.

20 In the drawings, Figure 1 represents a plan view of the mat; Fig. 2, a side view of said mat rolled; Fig. 3, a plan of a mat provided with a wiper; and Figs. 4 and 5 are modifications.

25 Reference being had to the drawings and the letters thereon, A indicates a mat composed of bars or sections *a*, of one or more coiled wire helices, and intervening sections 30 *b*, of bent wire, with which the bars or sections *a* are connected by intertwining, as shown.

The mat shown in Figs. 1 and 2 is designed 35 for indoor use, such as halls or vestibules, and is made thin, so that a door will readily pass over it in opening and closing. The bars or sections *a* in this instance are made of several thicknesses of coiled wire helices intertwined and of a width to suit circumstances, varying from one-half to an inch or 40 more. The wire helices are coiled in the usual manner and intertwined or screwed into each other as they proceed from the machine, and the strand or strands forming the edges of the bar are intertwined or screwed into the 45 sections *b* of bent wire. The sections *b* serve

to separate the bars *a* and form an open fabric, through which the tiling or oil-cloth or carpet in a hall or vestibule may be readily seen. These sections *b* may be bent to form

eyes *c*, as shown in Figs. 1, 2, 3, and 4, or they 50 may be in the form of a helix flattened, as shown in Fig. 5. It is obvious that the configuration of these uniting and separating sections may be greatly modified, and we do not therefore limit our invention to any especial form into which the wire may be bent.

The ends of the mat may be protected and finished by incasing the ends of the sections *a* and *b* in a transverse bar *d*, of rubber or equivalent material, such as gutta-percha or 60 linoleum, which forms protection against the fabric of ladies' garments catching on the jagged ends of the metal. This rubber bar *d* is applied by the use of a mold, and the rubber is embedded in the interstices of the wire 65 fabric of which the mat is composed while the rubber is in a plastic state and is subsequently vulcanized.

The mat thus constructed may be rolled transversely, as shown in Fig. 2, so as to be 70 readily and easily handled and transported.

For some purposes, such as railway and street cars, we may make the sections or bars *a* of one section of coiled wire, as shown in Figs. 4 and 5, or several sections may be intertwined in the same horizontal plane and the bars separated and held together by the sections *b*.

75 For indoor purposes, such as halls, stairs, or railway and sleeping cars, where ornamentation is desired, the mats may be made of different kinds of metal, such as steel and brass or copper.

For outdoor mats a rubber wiper *e*, having 80 roughened or serrated edges *ff* and a roughened or serrated upper surface *g*, is applied. This wiper is embedded in the body of the mat and projects a sufficient distance above the surface of the mat to afford convenient means for removing any offensive matter from 85 the soles and edges of a boot or shoe. The wiper may be attached in any desired part of the mat, and in large mats two or more wipers 90 may be applied.

The mat constructed as shown is very 95 light and pliable, capable of being made in great lengths and rolled for packing, handling, or transportation, while it is highly orna-

mental and performs all the service of the thick, heavy, and unwieldy metallic mats now in common use.

Having thus fully described our invention, 5 what we claim is—

1. A wire mat composed of a plurality of bars formed of coiled wire helices and intervening sections of continuous strands of wire crossing each other and connected at each 10 angle in the sections with the contiguous edges of the bars and close flexible coverings incasing the ends of the mat.

2. A wire mat composed of bars formed by 15 a plurality of intertwined wire helices in the same horizontal plane or planes and intervening diagonally-arranged continuous sections of strands of wire crossing each other and secured to the bars.

3. A wire mat composed of bars formed by 20 a plurality of intertwined wire helices in the same horizontal plane or planes and intervening diagonally-arranged continuous sec-

tions of strands of wire crossing each other and secured at the edges of the bars and having the ends of the bars and the intervening 25 sections incased in a close flexible covering.

4. A wire mat composed of bars of coiled wire helices and intervening sections of strands of wire having eyes or loops formed thereon, with which the bars are intertwined. 30

5. A wire mat composed of bars of a plurality of intertwined coiled wire helices separated and connected by intervening sections of strands of wire and provided with a flexible rubber wiper having roughened sides and 35 upper surface.

In testimony whereof we affix our signatures in presence of two witnesses.

JAMES E. EMERSON.
THOMAS MIDGLEY.
